UNITED STATES PATENT OFFICE

EUGEN PRESTINARI, OF IRVINGTON, NEW JERSEY, ASSIGNOR TO GEMEX COMPANY, OF NEWARK, NEW JERSEY, A CORPORATION OF NEW JERSEY

BRACELET CHAIN

Application filed June 14, 1929. Serial No. 371,011.

This invention relates to a chain for use as a bracelet for wrist watches or the like, and has for its principal object the formation of a thin, flexible band which when worn on the wrist for retaining a watch thereon will not interfere with the use of the wrist for writing and will not otherwise inconvenience the wearer.

A further object of the invention is to provide a bracelet structure which will withstand longitudinal strains without separation.

Another object is to provide a sheet metal construction for a bracelet which will present an attractive appearance when worn.

With these and other objects in view, the invention consists of certain novel features of construction, which will be more fully described in the detailed description following, and will be more particularly pointed out in the appended claim.

In the accompanying drawings:

Figure 1 is a top plan view on an enlarged scale of a chain formed in accordance with this invention;

Figure 2 is a plan view of a connecting link;

Figure 3 is perspective view of a connecting link, with the edges turned upwardly to form flanges, as in the finished chain;

Figure 4 is a sectional view on the line 4-4 of Figure 1, showing the relative positioning of the flanged link edges and the chain body members, and

Figure 5 is a sectional view on the line 5-5 of Figure 1, showing the relative heights of the body members and the link flanges.

It is found desirable, in the formation of thin bands or straps for securing a watch on a wrist, to produce the appearance of a hollow link construction and thus give the band a neat appearance while worn, and at the same time to reduce the manufacturing cost by simplifying the manufacturing procedure. I therefore connect together frame

links by open ended sheet metal body links, and turn the edges of the frame links upwardly to close the upper portion of the body link ends and to form an attractive border for the body links without detracting from the flexibility of the band or strap; this construction provides a thin band or strap which will withstand the longitudinal strain to which it is subjected without separation of the constituent parts thereof; and the following is a detailed description of the present embodiment of this invention illustrating the preferred structure by which these advantageous results may be accomplished.

Referring to the drawings, 10 designates the frame link, generally rectangular in shape and provided with a longitudinal rectangular opening 11 leaving end sections 12, 13 which, as shown, are preferably arcuate in form. A sheet metal connecting link 14 has wing portions 15, 16 which are folded around the sides of the frame links, as shown in Fig. 4, to form substantially rectangular links. The ends 12, 13 of the connecting link are turned upwardly, as shown in Figure 5, to form an attractive border, or margin, for the body links, completely closing the greater portion of the open ends of the body links so as to present an attractive appearance, and also to prevent cutting the wrist.

Each of the parts of this strap is of thin sheet stock, the thickness of the strap being twice the thickness of the body link stock plus the thickness of the frame link stock. The strap is flexible, is strong, and is extremely thin.

The foregoing description is directed solely towards the construction illustrated, but I desire it to be understood that I reserve the privilege of resorting to all variations and mechanical changes within the scope of the invention, as defined by the appended claim.

I claim:

A bracelet chain comprising a series of

generally rectangular-shaped frame links, each having a longitudinal slot therein, and sheet metal links each comprising a body portion with oppositely extending wings, each extending through the slot of a frame link seated directly in contact with the body portion and folded together with their edges abutting, and end sections on said frame links folded towards said body portions to form margins for said sheet metal links.

10 In testimony whereof I affix my signature.
EUGEN PRESTINARI.
